(57) **CLAIM**

We claim the ornamental design for a diving board, as shown and described.

DESCRIPTION

FIG. 1 is a perspective view of the design for a diving board; FIG. 2 is a front view of the design of FIG. 1, the rear view being a mirror image thereof;

FIG. 3 is a right side view of the design of FIG. 1, the left side view being a mirror image thereof;

FIG. 4 is a top view of the design of FIG. 1; and,

FIG. 5 is a bottom view of the design of FIG. 1.
